[57] ABSTRACT

An economical apparatus is provided for heating the surface of constructions such as a road, floor, wall, etc. which comprises at least two juxtaposed ferromagnetic pipes having a wall thickness of at least twice the skin depth of a.c. flowing therethrough and an insulated electric wire passing in series through each inside of said ferromagnetic pipes, both the ends of which are connected to an alternating current source. When an alternating current is passed through said insulated electric wire, a secondary current is induced along both the inner and outer skin portions of said ferromagnetic pipes and heat is generated therein.

Further, the electrically neutral points of the ferromagnetic pipes are connected to each other by an electric conductor and a fault detecting means responsive to a flow of current in the conductor is provided to disconnect the insulated wire from the alternating current source upon occurrence of an electrical fault in the apparatus.

APPARATUS FOR HEATING THE SURFACE OF CONSTRUCTIONS

The present invention relates to an improvement in the heat-generating pipes utilizing skin effect current, disclosed in U.S. Pat. No. 3,410,977 and U.S. Pat. No. 3,515,837. The inventor and assignee of these patents are the same with those of the present invention.

Firstly the background of the present invention will be given referring to the accompanying drawings.

FIG. 1 shows the principle of the heat-generating pipe utilizing skin effect current disclosed in the above-mentioned U.S. Pat. No. 3,410,977. In this figure, numeral 1 shows a ferromagnetic pipe such as a steel pipe, and terminals 6 and 6' at both the ends of the pipe are connected to an alternating current source 5 by an electric wire 2' and an insulated electric wire 2 which passes through the inside of the pipe.

When the resistivity of the material of the ferromagnetic pipe 1 is ρ ($\Omega \text{ cm}$); the specific permeability thereof is μ ; and the frequency of the alternating current source is f (Hz), the depth of skin of alternating current (a.c.), S (cm), is expressed by the following formula:

$$S = 5,030 \sqrt{\rho/\mu f} \quad (1)$$

If there is a following relationship (2) among the wall thickness t (cm), the inner diameter d (cm) and the length l (cm) of the pipe 1 and the above-mentioned S :

$$t > 2S, \quad l >>d \quad (2)$$

the current 3 supplied from the a.c. source 5 flows concentratedly through the inner skin portion 4 of the ferromagnetic pipe 1, and heat is generated only at the inner skin portion. In this case, substantially no voltage appears on the outer surface of the pipe, and hence even if the outer surface is contacted with human beings or animals, they sustain no injury, and also, the heat-generating pipe does not become a cause of fire. Thus, the heat-generating pipe can be utilized as a safe heat-generating pipe for heating e.g. the surface of a road, floor, wall, etc.

FIG. 2 shows the heat-generating pipe utilizing skin effect current disclosed in the above-mentioned U.S. Pat. No. 3,515,837. In this figure, numerals 7 and 8 show ferromagnetic pipes having the same specified conditions relative to the wall thickness and length as those of the pipe 1 of FIG. 1, the adjacent ends of the two pipes being each connected by a connecting means 13 or 14 having as low as impedance as possible. Numeral 9 shows an insulated electric wire passing through the insides of the two ferromagnetic pipes and connected to the terminals of the a.c. source 12. In this apparatus, the alternating current 10 passing through the electric wire 9 is a primary current, and the secondary current flows through the inner skin portions 11 of the ferromagnetic pipes to generate heat therein, and substantially no voltage appears on the outer surfaces of the ferromagnetic pipes 7 and 8, as in the apparatus shown in FIG. 1. Thus, this apparatus can be also utilized as a safe heat-generating pipe. Although the above-mentioned explanation is made referring to sin-

gle phase circuits, the principle of the polyphase circuit also is same as those of the simple phase circuits.

The advantages of the apparatuses shown in FIG. 1 and FIG. 2 over the MI cable or a plastic material-insulated cable which are usually used by directly laid under the surface of road, floor or the like, are that the insulated electric wires, which are liable to suffer damages, are protected by ferromagnetic pipes having a considerable mechanical strength; that, even if the insulated electric wire passing through the inside of the ferromagnetic pipe should suffer damages, they are readily replaced by new wires without digging up the road, floor, wall or the like; and that insulated electric wires of lower heat resistance or thinner electric wires are sufficient for the apparatuses shown in FIG. 1 and 2, because the major part of heat is generated at the inner skin portion of the ferromagnetic pipe, and the ferromagnetic pipe is contacted directly with a substance to be heated to make the transfer of heat easy, and hence the temperature of the insulated electric wire inside the pipe is relatively low.

However, the known heat-generating apparatuses shown in FIG. 1 and 2 have a drawback in that heat is generated only at the inner skin portion of the ferromagnetic pipe, and the outer skin portion is not utilized. Further, in the apparatus of FIG. 1, the larger the surface area to be heated, beneath which the ferromagnetic pipe 1 is distributed, the greater the number of bend parts to be provided. Thus, it becomes necessary to connect straight pipes with bend pipes by expensive on-the-spot welding. Also in the apparatus of FIG. 2, the connection by welding of the electric wires 13 and 14 having a low impedance is, as a matter of fact, carried out on the spot, and the cost becomes higher than the material cost of the ferromagnetic pipe such as steel pipe, in some cases.

The object of the present invention is to provide an apparatus for heating the surfaces of constructions such as a road, floor, wall, etc. which does not require expensive on-the-spot working, is safe and utilizes both the inner and outer skin portions of the ferromagnetic pipe as heat-generating portions, whereby about twice the quantity of heat generated by the above-mentioned known heat-generating apparatuses can be obtained.

The present invention resorts to an apparatus for heating the surface of constructions which comprises at least two juxtaposed ferromagnetic pipes having the wall thickness of at least twice the skin depth of a.c. flowing therethrough, and an insulated electric wire passing in series through each inside of said ferromagnetic pipes, both the ends of which are connected to an alternating current source, whereby when an alternating current is passed through said insulated electric wire, a secondary current is induced at both the inner and outer skin portions of said ferromagnetic pipes to generate heat there.

As the insulated electric wire passing through the inside of the pipes, there can be illustrated copper or aluminum wires coated with an insulated material such as organic high molecular weight substances.

As the surface of constructions, there can be illustrated the surfaces of a road, floor, wall, etc.

FIGS. 1 and 2 are schematic cross-sectional views for illustrating the principles of known heat-generating pipes utilizing skin effect current.

FIG. 3 is a schematic view for illustrating the principle of the induction heat-generating pipe of the present invention.

FIG. 4 is a schematic plan view of the apparatus of the present invention.

FIG. 5 is a cross-sectional view of FIG. 4 along the V-V line.

Next, the present invention will be further illustrated referring to the accompanying drawings.

The schematic view shown in FIG. 3, illustrating the principle of the present invention is the same as that shown in FIG. 2 except that the low impedance connections 13 and 14 of FIG. 2 are omitted. Thus, in the apparatus of FIG. 3, voltage appears also on the outer surfaces 19', 20' of ferromagnetic pipes 15 and 16. FIG. 3 will be explained further in detail. An insulated electric wire 17 passing through the inside of the ferromagnetic pipe 15, 16, forms a primary circuit together with an a.c. source 21, and an electric current 18 flows therethrough. Secondary electric current is induced in each of the ferromagnetic pipes 15, 16, and a circuit of the current is formed between the inner skin portion 19 and the outer skin portion 19' in the ferromagnetic pipe 15, while another circuit of the current is formed between the inner skin portion 20 and the outer one 20' in the ferromagnetic pipe 16, to generate heat at both the inner skin portion and the outer one. Such a secondary current is nothing but an eddy current.

In order to make the best use of the present invention, it is necessary that the wall thicknesses of the above-mentioned ferromagnetic pipes 15, 16 are at least twice the skin depth of a.c. flowing therethrough expressed by the formula (1).

As mentioned above, voltage appears also on the outer surface of the ferromagnetic pipe, in the apparatus of FIG. 3 on which the present invention is based, and hence if the substance to be heated is of a low resistivity, as in metal, there is a danger that the electric current flows to the substance to be heated.

However, in the heating of the surface of a road, floor, wall or the like, the substance surrounding the ferromagnetic pipes is generally an electrically insulating substance such as concrete, asphalt, etc., or a substance having a similar property, and hence if the voltage appearing on the outer surface of the ferromagnetic pipe is not so high, concrete, asphalt, etc. function as an insulating substances which do not give danger to human being or animals. Thus, the apparatus of FIG. 3 can be utilized as by heat-generating apparatus as well as those shown in FIGS. 1 and 2.

The length of each ferromagnetic pipe as required in the heating of the surface of a road, floor, wall or the like, is fortunately about 1 m to about 20 m. When steel pipes having a length of this extent are used as the ferromagnetic pipe and an alternating current of a commercial frequency of 50 - 60 Hz is used as an a.c. source, the voltage appearing on the outer surface of each ferromagnetic pipe is 0.5V to 5V, and hence the apparatus can be fully utilized for the above-mentioned purposes.

In the apparatus of FIG. 3, an insulation coating can be further applied on the outer surface of the ferromagnetic pipe. As the insulation coating, there can be illustrated coating with paint, coal tar, or the like, lining with polyvinyl chloride, polyethylene, or the like, or winding of insulating tape around the pipe. By applying such an insulation coating, the length of the steel pipe

allowable in the above-mentioned example, can be extended up to about 100 m.

FIG. 4 shows an embodiment of the present invention. In this figure, numeral 25 shows ferromagnetic pipes corresponding to 15, 16 in FIG. 3, and they are arranged in six parallel rows, the number of which, however, can be varied dependent on the area to be heated. The adjacent ends of these ferromagnetic pipes are connected by bends 32, 33, 34 made of an insulating material and a connecting box 35 so that the ferromagnetic pipes, the bends and the box can form a serial pipe. Bends 32, 33, 34 may be made of an electrically conductive material, such as steel, providing that insulating pieces are inserted in between the ferromagnetic pipes and the bends. Numeral 26 shows an insulated electric wire passing through the inside of the above-mentioned serial pipe and connected to electric wires 27, 28 which are connected to an a.c. source 36, at terminal boxes 30, 31 provided at both the ends of the serial pipe.

The bends 32, 33, 34 and connecting box 35, when the heating apparatus is used for preventing the surface of a road from freezing, for melting snow thereon or for the like purposes, are provided on the sides of road or the shoulder of road which is the part where there is not so frequent walking of human being or animals or traffic.

In the apparatus shown in FIG. 4, the left and/or right side ends of ferromagnetic pipes 25 may be accommodated in a duct or ducts allowing the insulated conductor 26 to pass therethrough. In this case, the ends of the ferromagnetic pipes must be electrically isolated from the duct or ducts.

In FIG. 5 showing a cross-sectional view along the V-V line of FIG. 4, the ferromagnetic pipes 25 are surrounded by an insulating substance or a substance having a similar property 43 which constitutes road, floor, wall or the like, such as asphalt, concrete, etc. The ferromagnetic pipes may be applied by an insulation coating 44.

As mentioned above, the heating apparatus of the present invention is of a construction in which voltage appears also on the outer surface of the ferromagnetic pipe, and hence if a fault should occur on the insulated electric wire, there is a possibility that the outer surface of the ferromagnetic pipe has a potential close to the voltage of the a.c. source dependent on the place of the fault.

Since the voltage of the a.c. source is far greater than that appearing on the outer surfaces of the respective pipes, such fault could lead to more serious accidents in the vicinity of the fault point unless it is detected so that any countermeasure can be taken. For this reason, some device capable of detecting faults should be incorporated into the heating pipe arrangement in the present application. For the purpose of providing such a device, a voltage detector is connected in the pipe arrangement as shown in FIG. 4.

As a method for preventing troubles from occurring from the above-mentioned accident, each one point, preferably each one electrically neutral point, on the outer surface of each ferromagnetic pipe is connected to each other by an electrical conductor which is further connected to a voltage-detector. One example thereof is illustrated in FIG. 4, where each ferromagnetic pipe is connected to each other by an electric wire 39, at each one electrically neutral point 42 on the

outer surface of each pipe, that is, each one point on the outer surface of the middle part in the longitudinal direction, of each steel pipe, and the electric wire 39 is further connected by an electric wire 40 to one terminal of a voltage-detector 38, another terminal of the detector being connected by an electric wire 41 to a specific point of voltage at an a.c. source 36. When the heating apparatus of the present invention is under normal operation, no voltage occurs in the electric wire 39 or no current flows therein, and hence the detector 38 for detecting a fault does not operate.

However, if a fault should occur in the insulated electric wire 26 in one of the ferromagnetic pipes 25, the potential of the ferromagnetic pipe is elevated to generate an electric current in the electrical conductor 39 connected to the pipe, followed by actuating the detector 38, and breaking the connection with the a.c. source by means of a breaker 37.

Although such a fault in the electric wire 26 can be detected by a known fault-detector and circuit, the detection by way of such a conventional detecting circuit becomes difficult or expensive if the ferromagnetic pipes are surrounded by a substantially insulating material such as concrete or asphalt. However, according to the above-mentioned method of the present invention, an easy and highly sensitive detection is possible.

As mentioned above, it is preferable that each one point on the outer surface of each ferromagnetic pipe 25, to be connected by the connecting conductor 39, is at the neutral point of the pipe or near this point. The reason will be explained as follows referring to FIG. 3.

When the connection 22 carried out at each neutral point of the ferromagnetic pipes 15, 16 or near this point, is compared with the connection 22' carried out at each one adjacent end of the pipe, the potential difference between the other adjacent ends 23 and 24 in the former case becomes half that of the latter case.

What is claimed is:

1. An apparatus for heating the surface of constructions of an electrically insulating nature which comprises, at least two juxtaposed ferromagnetic pipes each having a length ranging from about one meter to about twenty meters and wall thickness of at least twice the skin depth of the alternating current flowing therethrough, an insulated electric conductor passing in series through the inside of each of said ferromagnetic pipes, the ends of said conductor being connected to the opposite terminals of an alternating current source, said pipes being electrically separated from each other, the respective electrically-neutral points of the outer surfaces of said ferromagnetic pipes being connected to each other by a further electric conductor, and voltage detecting means responsive to a flow of current in said further conductor to detect a fault in said insulated electric conductor and disconnect said insulated conductor from said alternating current source, whereby when an alternating current from the source is passed through said insulated electric conductor a secondary current is induced in both the inner and outer skin portions of said ferromagnetic pipes to generate heat there.
